ATTORNEY

UNITED STATES PATENT OFFICE.

CARL A. HALL, OF CARTHAGE, NEW YORK.

WIRE-STRETCHER.

1,311,390.

Specification of Letters Patent. Patented July 29, 1919.

Application filed November 22, 1917. Serial No. 203,426.

To all whom it may concern:

Be it known that I, CARL A. HALL, a citizen of the United States, residing at Carthage, in the county of Jefferson and State of New York, have invented certain new and useful Improvements in Wire-Stretchers, of which the following is a specification.

This invention relates to wire stretchers and more particularly to a device adapted to be manually operated for the purpose of stretching strands of wire particularly those constituting a fence whereby the wires may be drawn taut and rigidly held in a position to permit them to be fastened to a fence post during the construction of the fence.

The invention further aims at the provision of a wire stretcher of this character that may be longitudinally adjusted for securing the proper hold on the strand of wire which is to be stretched whereby the operating lever may be properly set to obtain a long leverage to produce the stretching operation.

The invention further aims to provide a device of this character that will include a simple and efficient post engaging means whereby the operating lever may be held in position for permitting the lever to be turned while longitudinal adjustment of the lever may be obtained when desired.

A further object of this invention is the provision of a wire stretcher which consists of comparatively few parts and is simple in construction, but durable and well adapted to withstand the rough usage to which devices of this character are ordinarily subjected.

For a full description of the invention and the advantages and merits thereof, reference is to be had to the following description and the accompanying drawings, wherein is illustrated the preferred form of my invention, in which:

Figure 1 is a plan view of the device showing the same mounted in connection with a fence post and attached to a strand of wire.

Fig. 2 is a fragmentary side elevation the operating lever being shown in cross section and,

Fig. 3 is a detail elevation on an enlarged scale of a portion of the wire clamping element.

Referring to the drawing, wherein is illustrated the preferred form of my invention, like numerals of reference indicate corre-

sponding parts throughout the several views, the fence post A is adapted to have the wire strand B attached thereto and when placing this strand in position it is necessary to tightly stretch the wire so that it may be held taut after being attached to the fence post.

Surrounding the fence post is a fastening chain 1 which has one end rigidly secured to a plate 2 which is elongated and is disposed vertically on one side of the fence post when the device is mounted in position. At the marginal edge of the plate 2 opposite to that to which the chain is attached I have provided a yoke 3 which has retaining fingers 4 laterally spaced apart for a distance equal to about the size of one of the links of the chain whereby one of the links may be placed in the yoke to fixedly hold the chain to the post. Integrally formed with the plate 1 is a pair of flanges 5 which, when the plate is disposed vertically as shown in Fig. 2 of the drawing, will be arranged in superposed relation to provide an operating space 6 between the flanges. Each flange 5 is provided with a suitable opening through which a pivot bolt 7 is extended and an operating lever 8 is mounted upon this bolt for facilitating the stretching of the wire. As shown to advantage in Fig. 1 of the drawing, the operating lever includes an elongated bar 9 one end of which serves as a handle 9 for the device while the opposite end is curved to provide an arcuate portion 10 the terminal of which is pivotally connected to a fastening device 11 for connecting the strand of wire to the stretcher. This fastening device includes the flange 12 which has a corrugated surface and which is adapted to cooperate with a pivoted pawl 13 also having a corrugated portion which cooperates with the corrugations on the flange 12 to tightly engage the strand of wire to engage it to the fastening device. In this manner the forward curved end of the operating lever is connected to the strand of wire.

In the bar 8 near the end of the straight portion thereof, I have provided an elongated slot 14 which communicates with a series of longitudinally spaced notches 15. The bolt 7 is adapted to be extended through the slot 14 and to be received in any one of the notches 15. By moving the lever so that the bolt is received in the slot it will be obvious that the operating lever may be

longitudinally adjusted to obtain the desired leverage. When this is secured, the lever is moved until one of the notches receives the bolt whereupon a suitable hold may be obtained for the purpose of acting as a focus to pull the wire as shown to advantage in Fig. 1 of the drawing.

From the foregoing it will be observed that a very simple and durable wire 10 stretcher has been provided the details of which embody the preferred form. I desire it to be understood, however, that slight changes in the minor details of construction may be made without departing from the 15 spirit of the invention or the scope of the claim hereunto appended.

Claim.

In a wire stretcher, an operating lever

including an elongated bar having one end curved to provide an arcuate portion, a 20 fastening device carried at the terminal of the arcuate portion for receiving the wire, the said elongated bar being provided near the end of the straight portion thereof with a slot, and a series of longitudinally spaced notches opening into the slot; in combination with a fence post having a plate 25 mounted thereon and carrying a pivot bolt extended through the said slot and adapted for reception in any of the said notches. 30

In testimony whereof I affix my signature in presence of two witnesses.

CARL A. HALL.

Witnesses:
